US00D888948S

(12) **United States Design Patent** (10) **Patent No.:** **US D888,948 S**
(45) **Date of Patent:** **** Jun. 30, 2020**

(54) **INTRAVAGINAL DEVICE**

(71) Applicant: **Renovia Inc.**, Boston, MA (US)

(72) Inventors: **Marc D. Beer**, Sudbury, MA (US);
Jose Bohorquez, Boston, MA (US);
Samantha J. Pulliam, Boston, MA (US);
Jessica L. McKinney, Boston, MA (US)

(73) Assignee: **Renovia Inc.**, Boston, MA (US)

(**) Term: **15 Years**

(21) Appl. No.: **29/686,034**

(22) Filed: **Apr. 2, 2019**

(51) LOC (12) Cl. **24-02**

(52) U.S. Cl.

USPC **D24/141**

(58) **Field of Classification Search**

(57) **CLAIM**

The ornamental design for an intravaginal device, substantially as shown and described.

DESCRIPTION

FIG. 1 is a front and left side perspective view of an intravaginal device embodying the claimed design.

FIG. 2 is a front view of the intravaginal device of FIG. 1

FIG. 3 is a rear view of the intravaginal device of FIG. 1

1.

FIG. 5 is a left side view of the intravaginal device of FIG. 1.

FIG. 6 is a top view of the intravaginal device of FIG. 1; and,

FIG. 7 is a bottom view of the intravaginal device of FIG. 1.

1 Claim, 4 Drawing Sheets
